Inventor:

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 14,922, dated March 25, 1884.

Application filed February 13, 1884. Term of patent 3½ years.

To all whom it may concern:

Be it known that I, SARAH JANE SHIELS, of the city, county, and State of New York, have invented and produced a new and original Design for a Pattern of a Miss's Costume, (numbered 9,107;) and I do hereby declare that the engraved prints accompanying this specification convey to any one accustomed to using paper patterns a clear understanding of how a garment made up by the pattern will appear.

The design shows a walking-skirt and an over-dress. The skirt displays on its front gore a short, slightly-pointed drapery, that exhibits crosswise draping-plaits. The overdress displays closely-fitted fronts, that are short and pointed at each side of the closing and long

and plain at the sides; a short, closely-fitted basque-back, exhibiting an added double box-plaited drapery falling in shell fashion at the top; coat-sleeves, and a rolling collar, the sides and back of the overdress falling nearly to the bottom of the skirt.

What I claim as my invention, and desire to secure by Letters Patent, is—

The design for a miss's costume, as shown in the engraved prints accompanying this specification.

SARAH JANE SHIELS.
